UNITED STATES PATENT OFFICE.

GEORGE L. RANKIN, OF MUNHALL, PENNSYLVANIA.

SCHOOL-DESK.

1,346,976.

Specification of Letters Patent. Patented July 20, 1920.

Application filed August 18, 1919. Serial No. 318,071.

To all whom it may concern:

Be it known that I, GEORGE L. RANKIN, residing at Munhall, in the county of Allegheny and State of Pennsylvania, a citizen of the United States, have invented or discovered certain new and useful Improvements in School-Desks, of which improvements the following is a specification.

The object of my invention is to provide 10 a combined school desk and chairs whereby a larger number of pupils may be comfortably seated and adequately provided with desk facilities than is possible by the use of the usual types of desks and chairs, and 15 also to provide a school desk which may be adjusted to the requirements of different sized pupils, and which affords opportunity for janitors to properly clean a school room floor.

20 My invention is illustrated in the accompanying sheet of drawings which form part of my specification. Figure 1 is a side view of the desk and chairs, Fig. 2 a plan view thereof, a portion of the top being broken 25 away; and Fig. 3 a detail sectional view taken on the line III—III, Fig. 1.

The desk which I provide has a plurality of sides and a top so constructed that a pupil may work from each side of the desk. 30 In the illustrative embodiment of the invention the desk is square, having four sides 1, 1^a, 1^b and 1^c, and the top 2 has four working faces 3, 3^a, 3^b and 3^c, each of which may slope upwardly, as indicated. The space 35 between the top 2 and bottom 4 of the desk is divided by partitions 5 into book compartments 6, one of which is open at the right hand portion of each side of the desk. If desired, the bottom 4 may be made of 40 screen-like metal, such as a perforate plate, so that dust and other foreign and unsanitary matter will not readily accumulate in the book compartments.

The desk is supported by vertically adjustable legs, arranged one at each corner, and a chair is pivotally mounted on each leg so that it may swing horizontally. Preferably, each leg consists of a cylindrical tube 7 having oppositely threaded ends engaging 50 flanged sleeves 8 and 9, the flanges of the sleeves 8 being attached to the desk bottom 4, and those of the sleeve 9 being adapted to be attached to a supporting floor 10. To hold tubes 7 in their adjusted positions, 55 the sleeves 8 may be provided with set screws 11.

Each chair preferably consists of a wire back 15 and a comfortable saddle seat 12 attached to the outer end of a bracket 13, at the inner end of which there are formed two sleeves 14 and 14^a. Between these sleeves there is a spring for holding the chair yieldingly toward a side of the desk. The spring preferably comprises oppositely coiled sections 16 and 16^a having their outer 60 ends looped over, or otherwise secured to, the top and bottom of the bracket 13. Between the coil sections a pin 17 engages the loop in the spring and extends into the tube 7. The bracket 13 is supported by a pin 18 70 extending through the tube 7 just below the sleeve 14^a.

In Fig. 2 one of the chairs is shown in its outward position, that is to say, the position it occupies when a pupil is working on 75 the desk, and the other seats are shown in their inward positions adjacent to the sides of the desk. That the spring 16, 16^a may not exert pressure upon a chair when in such outward position, the bottom of the sleeve 14^a 80 may be provided with a groove 19 adapted to receive the pin 18 as shown in Fig. 3. For limiting the inward position of the chair, the lower side of the bracket 13 may be provided with a lug 20 adapted to engage 85 the outer end of the pin 18. The chairs are, however, not limited to the two positions indicated. Each may swing through an arc of about 180°, so that, when desired, all the pupils may face in one direction.

By equipping school rooms with the combined desks and chairs which I provide, a large economy of school room space is effected, thus making it possible to accommodate more pupils in one room, or to arrange the desks so that each room will have ample free floor space for physical exercises. Each desk may, by turning the leg sections 7, be vertically adjusted to best meet the needs of different sized pupils; and 100 with respect to such adjustment, it will be observed that the vertical movement of the desk and chairs, is effected simultaneously, the chairs being raised or lowered just half as much as the desk, assuming, of course, 105 equal pitches of the threads at the opposite ends of the tubes 7. It is also characteristic of my invention that the supports for desks and chairs offer a minimum of obstacles to the proper sweeping or other cleaning of the 110 floor. In effect, there is but a single support for the desk and chair of each pupil.

According to the provisions of the patent statutes, I have described the principle and operation of my invention together with the construction which I now consider to represent the best embodiment thereof. However, I desire to have it understood that, within the scope of the appended claims, my invention may be practised by other forms of construction than that specifically shown and described.

10 I claim as my invention:

1. The combination of a school desk having a plurality of sides and a top affording a working face from each of said sides, a leg including a vertically adjustable section at each corner of the desk, and chairs pivoted on the vertically adjustable leg sections, whereby the adjustment of the leg sections effects a simultaneous adjustment of the elevation of both desk and chairs.
- 15 2. The combination of a school desk having a plurality of sides and a top affording a working face from each of said sides, a

leg at each corner of the desk, each leg including a section having opposite screw threads at its ends, and chairs pivoted on said leg sections whereby the turning of said leg sections simultaneously adjusts the desk and chairs different relative amounts, each of said chairs being spring pressed toward one side of said desk.

25 3. The combination of a school desk having a plurality of sides and a top affording a working face from each of said sides, a leg at each corner of the desk, each leg including a section having opposite screw threads at its end, and chairs pivoted on said leg sections, whereby the turning of said leg sections simultaneously adjusts the desk and chairs different relative amounts.

35 40 In testimony whereof I have hereunto set my hand.

GEORGE L. RANKIN.
